GEORGE L. KOLLOCK AND ROBERT P. MARTIN, OF SEATTLE, WASHINGTON, ASSIGNEES
TO UNIVERSAL HAMMER COMPANY, OF SEATTLE, WASHINGTON, A CORPORATION
OF WASHINGTON.

AUTOMATIC HAMMER.

1,273,873.

Specification of Letters Patent. Patented July 30, 1918.

Application filed November 9, 1917. Serial No. 201,149.

To all whom it may concern:

Be it known that we, GEORGE L. KOLLOCK, a citizen of the United States, residing at Seattle, in the county of King and State of Washington, and ROBERT P. MARTIN, a citizen of the United States, residing at Seattle, in the county of King and State of Washington, have invented certain new and useful Improvements in Automatic Hammers, the following being a full, clear, and exact disclosure of the one form of our invention which we at present deem preferable.

For a detailed description of the present form of our invention, reference may be had to the following specification and to the accompanying drawing, wherein—

Figure 1 is a longitudinal and

Fig. 2 a transverse section of our device.

Our invention relates to an automatic hammer wherein a reciprocating striker is operated by a spring that is periodically tensioned and released by means of a motor-driven cam. Our device herein claimed involves particularly an arrangement for rotating the cam which is of annular form and encircles the striker, the said arrangement being such as to provide a free space for the working movement of the head and the cam-rollers of the striker.

Referring to the drawings, A represents a cylindrical form of electric motor forming one section of the body of the hammer and having at its rear end a handle B and at its other end a hollow enlargement adapted to be screwed on one end of a hollow casing which forms the remaining part of the hammer body. This casing contains the reciprocating striker D, actuated by spring E and the motor-driven cams and gears for alternatively tensioning and releasing the spring. The cam F, which is of the ratchet or saw-tooth type, is annular in form and is mounted on the face of a cam gear-wheel G which is mounted to rotate on the transverse disk T with intervening friction balls. The cam and gear-wheel are concentric with the striker D and surround the upper end thereof. The striker at its lower end carries a flange-nut D² against which bears one end

of the actuating spring E, the opposite end 50 of which abuts against the transverse disk R which also is provided with a central guide-bearing for the striker. The upper end of the striker is squared to prevent rotation and protrudes through the annular cam where 55 it is provided with an enlarged head D¹. On head D¹ are mounted the cam-rollers W, here shown as three in number so as to produce three strokes of the striker for each rotation of the cam. The gear-wheel G 60 meshes with a pinion K on a counter-shaft H which carries a pinion O that is driven by a pinion S on the motor shaft through an idler pinion R. By this arrangement the cam which surrounds the striker is rotated without interfering with the end-to-end relation of the motor shaft and striker, while allowing the latter a free space in which to operate without coming into contact with the motor pinion S. 70

What we claim as new and desire to secure by Letters Patent is:

1. An automatic hammer comprising a reciprocating striker, an actuating spring therefor, a motor having its shaft in line 75 with the striker but separated therefrom by a distance equal to the range of reciprocation of the striker an annular ratchet cam surrounding the striker and engaged thereby and a gearing connection between the 80 cam and motor including a counter-shaft at one side of the cam and suitable pinions.

2. An automatic hammer comprising a reciprocating striker, an actuating spring therefor, an annular ratchet-cam surrounding the upper part of the striker and having its working surface on its upper side, a cam roller mounted on the striker above the cam and engaging the said working surface, a gear wheel concentric with the cam outside 90 of the said working surface, an operating motor having its shaft in line with the striker and a driving connection between the said cam gear and the motor shaft.

Signed at Seattle, Washington, this 30th 95 day of October, 1917.

GEORGE L. KOLLOCK.
ROBERT P. MARTIN.
